UNITED STATES PATENT OFFICE

168,332

BOTTLED LIQUID DISPENSING UNIT

Gaspari H. Cannella, Brooklyn, N. Y.

Application September 7, 1951, Serial No. 16,571

Term of patent 3½ years

(Cl. D2—3)

To all whom it may concern:

Be it known that I, Gaspari H. Cannella, a citizen of the United States of America, residing at Brooklyn, State of New York, have invented a new, original, and ornamental Design for a Bottled Liquid Dispensing Unit, of which the following is a specification, reference being had to the accompanying drawing, forming part thereof.

Figure 1 is a perspective view showing the top, front and one side of a bottled liquid dispensing unit embodying my new design. The sides are substantially the same.

I claim:

The ornamental design for a bottled liquid dispensing unit, substantially as shown and described.

GASPARI H. CANNELLA.
